MOVABLE UTILITY FREEZER CART

Richard A. Gottlieb, Oak Park, Mich.

Application May 23, 1957, Serial No. 46,309

Term of patent 3½ years

(Cl. D14—3)

The figure is a fragmentary perspective view of a movable utility freezer cart, showing my new design.

The conventional wheel is shown broken away for convenience of illustration. The other side and end not shown are plain.

I claim:

The ornamental design for a movable utility freezer cart, substantially as shown and described.
